UNITED STATES PATENT OFFICE.

CHARLES H. FRANZ, JR., OF MILWAUKEE, WISCONSIN, ASSIGNOR TO THE HEINN CO., OF MILWAUKEE, WISCONSIN.

BINDER.

Application filed March 23, 1923. Serial No. 627,003.

To all whom it may concern:

Be it known that I, CHARLES H. FRANZ, Jr., a citizen of the United States, and resident of Milwaukee, in the county of Milwaukee and State of Wisconsin, have invented certain new and useful Improvements in Binders; and I do hereby declare that the following is a full, clear, and exact description thereof.

10 This invention relates to binders and is particularly directed to loose leaf binders, which are adapted to be carried from place to place.

In binders such as those used by traveling salesmen, it has been customary to provide substantial covers which fully protect the front and back of the pages but exposed the margins to dust and rain. This necessitated either the complete wrapping 20 of the catalogue or book or the provision of a separate case therefor, but even with these precautions the leaves soon become unsightly from the soot and dirt which rapidly accumulated upon such leaves.

25 This invention is designed to overcome the above noted defects, and objects of such invention are, therefore, to provide a binder for loose leaf books, such as catalogues, which will not only form the backs but will also fully and adequately protect all portions of the book from dust or rain, which will accommodate a large number of loose leaves, which permits their ready removal or insertion, and which may be readily 30 opened out flat to fully display any desired sheets and which may be instantly closed to thereby completely house the sheets.

An embodiment of the invention is shown in the accompanying drawings, in which—

40 Figure 1 is a perspective view showing the binder and the enclosed sheets opened out flat.

Figure 2 is a perspective view showing the device in the closed position.

45 Figure 3 is a side elevation partly in section, to illustrate the interior construction, such figure corresponding roughly to a section on the line 3—3 of Figure 2.

Figure 4 is a sectional view on the line 50 4—4 of Figure 3.

The binder comprises a pair of binding strips 1 and 2 of reinforced and sturdy construction, which are adapted to receive between them the loose sheets 3. A pair of 55 back plates 4 and 5 extend inwardly from

the binding strips and are overlapped and slidably related, as may be seen from Figures 1 and 3. Any desired means may be employed for holding the binding strips in engagement with the leaves, for instance, an expansion bolt 6 and a sleeve 6' may be employed, such sleeve being conveniently attached to the back plate 5, as illustrated in the drawings. These expansion bolts and associated sleeves may extend through apertures in the sheets in the usual manner.

A pair of reinforced covers, 7 and 8, are provided and are attached to the corresponding binding strips by means of flexible hinges, as indicated at 9 and 10, preferably formed from leather or similar easily manipulated material. A convenient way of attaching these strips to the cover is illustrated in Figure 3, from which it will be seen that the strips are received within an inner ply of the cover and the remaining plies thereof and stitched in position. This construction forms a waterproof joint between the covers and the binding strips. Each of the covers is provided with a U-shaped strap member, having its legs 11 stitched across the face of the cover, as illustrated in Figures 2 and 3, to form a secure attachment for the curved portion 12 thereof, which portion is utilized to form a composite handle. In this manner not only are the covers further reinforced, but the strain from the handles is distributed over a material portion of the covers and is not localized at any one point. If desired, the curved handle portions 12 may have reinforcing rods 13, (see Figure 3), to stiffen them. A strap 14 may be attached to one of the handle portions, and may be provided with snap fasteners so that it may be wrapped completely around both of the portions of the composite handle and snapped in place to form a convertible handle and a simple means for holding the covers in closed position.

In order to protect the marginal edges of the book from dirt, dust and rain, inwardly directed flanges are provided along the three free margins of the covers. The flange 15 of the cover 8 may be overlapped by the flange 16 of the cover 7, and it is to be noted that these flanges overlap a material distance so as to form an effective and serviceable protecting joint to prevent entrance of harmful matter. It is to be

noted that the flanges continue in unbroken formation completely around the three edges of the cover and are free from the back plates 4 and 5 to permit the complete opening up of the book, as illustrated in Figure 1. When, however, the book is closed, the flanges 15 and 16 overlap the end margins of the back plates, as may be seen from Figures 2 and 4, thereby completely protecting the leaves from the entrance of rain or dust.

It will be seen that a binder has been provided which is adapted to accommodate any desired number of leaves, and which is at all times securely attached to the leaves. This provides a binder which in effect forms a portion of the composite book.

It is further to be noted that the overlapping back plates and the overlapping flanges 15 and 16 completely house the leaves, and such housing is instantly secured merely by closing the book. This protects the book at all times when it is not in actual use, and does not necessitate the carrying of an auxiliary case for the book.

I claim—

1. A readily portable book comprising a pair of binding strips, leaves carried therebetween, a pair of stiff covers hinged to said strips, telescopic flanges carried by the free edges of said covers to completely house the leaves when the book is closed,

and a pair of strap handles secured to said covers and adapted to form a composite handle when said book is closed. 35

2. A binder for loose leaves comprising binding strips, adjustable means connecting said strips and binding the leaves between them, a pair of overlapping back members extending from said strips, relatively stiff covers hingedly joined to said strips, and flanges extending inwardly from the free edges of said covers and telescopically related to completely house the leaves when said covers are closed. 40 45

3. A binder for loose leaves comprising a pair of binding strips adapted to hold the leaves between them, adjustable bolts connecting said strips, a pair of slidably related overlapping back plates carried by said strips, a pair of reenforced covers joined to said strips by flexible material, inwardly directed telescopic flanges carried by said covers and adapted to overlap the ends of the back plates, and a U-shaped strap for each cover having its legs secured across the face of its corresponding cover and having its curved portion projecting therefrom. 50 55

In testimony that I claim the foregoing 60 I have thereunto set my hand at Milwaukee, in the county of Milwaukee, and State of Wisconsin.

CHARLES H. FRANZ, JR.
